CLAIM

The ornamental design for a make-up kit, as shown and described.

DESCRIPTION

FIG. 1 is a perspective view from above showing my new design;

FIG. 2 is a side elevational view of my design;

FIG. 3 is a front elevational view of my design;

FIG. 4 is a top plan view of my design;

FIG. 5 is a bottom plan view of my design; and,

FIG. 6 is an exploded and internal view of the make-up kit but the pair of applicators form no part of the design. The broken line showing of the pair of applicators each having circular ends separated by an elongated section is for illustrative purposes and forms no part of the claimed design.

FIG. 1

FIG. 3

FIG. 4

FIG. 5
